UNITED STATES PATENT OFFICE.

WILLIAM C. CODMAN, OF PROVIDENCE, RHODE ISLAND, ASSIGNOR TO GORHAM MANUFACTURING COMPANY, OF PROVIDENCE, RHODE ISLAND, A CORPORATION OF RHODE ISLAND.

DESIGN FOR A BACK OF BRUSHES OR SIMILAR ARTICLES.

41,265.

Specification for Design.

Patented Mar. 28, 1911.

Application filed January 20, 1911. Serial No. 603,760. Term of patent 14 years.

To all whom it may concern:

Be it known that I, WILLIAM C. CODMAN, a subject of the King of Great Britain, residing at Providence, in the county of Providence and State of Rhode Island, have invented a new, original, and ornamental Design for the Back of a Brush or Similar Article, reference being had to the accompanying drawing.

The figure in the drawing is a plan view of the back of a brush, showing my design.

I claim—

The ornamental design for a back of a brush or similar article, as shown.

WILLIAM C. CODMAN.

Witnesses:

ADA E. HAGERTY,

J. A. MILLER.

Copies of this design may be obtained for five cents each, by addressing the "Commissioner of Patents, Washington, D. C."
